16 Claims. (Cl. 66—70)

ABSTRACT OF THE DISCLOSURE

A knitting machine having a single flat needle bed provided with a plurality of sinker elements and a plurality of needles slidably aligned for movement in the forward and rearward directions between the sinker elements, and an apparatus for transferring loops suspended on selected needles at intervals of one or more needles to needles adjacent the selected needles.

This invention relates to improvements in knitting machines. More particularly, the invention concerns a knitting machine having a single flat needle bed, a large number of sinker elements aligned parallelly in a row at constant intervals across the forward edge of the needle bed in the longitudinal direction thereof, a large number of latch needles similarly aligned in a row alternately between the sinker elements in the needle bed that they can slide forward and return perpendicularly to the longitudinal direction of the needle bed, and a carriage with cams for accomplishing knitting upon being moved reciprocatingly along the longitudinal direction of the needle bed thereby to actuate the latch needles in succession.

It is an object of the invention to provide a knitting machine, particularly a hand knitting machine, of the type wherein latch needles are used, in which, by appropriately selecting the necessary latch needles, the transfer of loops suspended from said needles to respective adjacent needles is automatically accomplished, whereby openings in the knitted fabric can be accurately formed, and whereby knitting operations such as knitting of laces and lace-form patterns can be easily and practically carried out.

According to the present invention, there is provided a knitting machine having, as its essential features: (1) latch needles which are so adapted and arranged that at least the forward end part of each latch needle can pass over an adjacent sinker element and move relative to an adjacent latch needle; (2) a latch needle actuating carriage which is so mounted across the needle bed that it can slide in the longitudinal direction of the needle bed; and (3) a means provided in said carriage for actuating the latch needles so that certain predetermined latch needles spaced from each other and having one or more needles therebetween can be approached relatively, at least at their forward parts, respectively to adjacent latch needles, each of the two latch needles so caused to approach relatively to undergo relative movement in their sliding direction, thereby causing one of said two latch needles to pass into a needle loop suspended from the other needle, and, at the same time, causing the needle suspending this loop to knock over and be extracted from the loop.

In the practice of the invention, it is possible to form the mechanism for operating the latch needle actuating carriage so that, in order to cause two adjacent latch needles to approach each other, for example, one of two mutually adjacent needles is caused, at least at its forward end part, to move transversely to approach the other nee-

2

dle, and so that the latch needle which has so moved is caused to return to its original position between adjacent sinker elements.

Furthermore, as means for causing one of each pair of mutually adjacent latch needles to approach the other, it is possible also to provide in the latch needle actuating carriage a mechanism whereby one of the needles is caused to project beyond the forward ends of the sinker elements, and the forward part of this projecting latch needle is engaged to cause this needle to move in the longitudinal direction of the needle bed and approach the other adjacent latch needle. For causing a certain selected latch needle to approach the mutually adjacent latch needle, it is advantageous to so fabricate this needle that it is elastically flexible at least in the longitudinal direction of the needle bed.

The nature, principle, and details of the invention will be more clearly apparent from the following detailed description with respect to preferred embodiments of the invention, when read in conjunction with the accompanying drawings in which FIGS. 1 through 6, FIGS. 7 through 11, FIGS. 12 through 14, and FIGS. 15 through 20 respectively illustrate first, second, third, and fourth embodiments of the invention, and in which:

FIG. 1 is a rear view showing a latch needle actuating carriage of the first embodiment of the invention, said carriage being adapted to transfer a yarn loop from a latch needle to an adjacent latch needle;

FIG. 2 is a sectional view taken in the plane indicated by line 2s—2s in FIG. 1;

FIG. 3 is a sectional view taken in the plane indicated by line 3s—3s in FIG. 2;

FIGS. 11(Ia), 11(IIIa) and 11(IXa) are plan views showing latch needles in positions corresponding respectively to FIGS. 11(I), 11(III) and 11(IX);

FIG. 12 is a rear view showing the latch needle operating carriage of the third embodiment of the invention, said carriage being adapted to transfer a yarn loop from a latch needle to an adjacent latch needle;

FIG. 13 is sectional view taken in the plane indicated by line 13s—13s in FIG. 12;

FIG. 14(I) through 14(VIII), inclusive, are sectional views taken in the planes respectively indicated by lines I through VIII in FIGS. 12 and 13 and show successive steps in the loop transfer operation of the latch needles;

FIGS. 14(Ia), 14(IVa), 14(VIIa), and 14(VIIIa) are plan views showing latch needles in positions corresponding respectively to FIGS. 14(I), 14(IV), 14(VII), and 14(VIII);

FIG. 15 is a rear view of a latch needle actuating carriage of the fourth embodiment of the invention;

FIG. 16 is a side view of the carriage shown in FIG. 15;

FIG. 17 is a fragmentary sectional view taken in the plane indicated by line 17s—17s in FIG. 15;

FIG. 18 is a sectional view taken in the plane indicated by line 18s—18s in FIG. 16;

FIGS. 19(a) through 19(h), inclusive, are sectional views taken in the planes indicated respectively by lines *a* through *h*, inclusive, in FIGS. 15 and 18 and indicate successive steps in the operation of the needles in the fourth embodiment of the invention;

FIG. 20 is a fragmentary perspective view indicating one stage of the operation of the needles;

FIGS. 21(a) to 21(h) show the loop transferring operation of an other embodiment according to this invention; and

FIG. 22 is a schematic plan view of the machine according to present invention.

Throughout the drawings, like parts are designated by like reference numerals and characters. The knitting machine such as shown in FIG. 22 comprises a needle bed 1, a large number of sinkers 3 which are fixed to the needle bed forward edge 2 along the needle bed 1 in such a manner that they are parallelly arranged and are at certain intervals and directed in the direction perpendicular to the longitudinal direction of the needle bed. A large number of latch needles N are arranged between sinkers so as to be forwardly slid and retracted to their original positions, and a knitting carriage KC provided with cams is adapted to operate said latch needles for carrying out the knitting operation when the carriage is slid rightward and leftward along the needle bed in the longitudinal direction thereof. This type of machine is conventional and is well-known. Because, the present invention relates to improvements of said conventional machine, the details of the construction and operation of the machine itself are omitted herein and only the improved parts of the machine will be described below.

Referring to a first embodiment of the present invention, a latch needle operating carriage 4 as shown in FIGS. 1 to 6 is used for transferring a yarn loop from a latch needle to the adjacent latch needle.

The carriage 4 is provided at its sliding side with various cam members C₁ to C₇ a latch engagement member 5 and other members. The operation and construction of said cam members, latch engagement members and other members will be understood from the following description.

Referring to FIGS. 1 to 6; among the latch needles N participating in the knitting operation, a needle N₂ suspending a yarn loop and corresponding to a position where an opening is to be made is advanced slightly relative to the other needles and is disposed on the needle bed 1 as indicated in FIG. 1(Ia), said needle bed 1 being provided with a large number of sinkers 3 fixed thereto at the forward edge 2 of the needle bed.

The cam members are formed so that the needle N₁ passes through the needle path *x* of the carriage 4, and the needle N₂ is prepared for passing through the loop transfer needle path *y*. The needle N₂ the hook tip of which is projecting beyond the sinker 3 in the position shown in FIG. 6(I) advances in accordance with the inclination of the needle path *y* to the position indicated in FIG. 6(II), whereupon a latch engagement member 5 extending downwardly from the carriage 4 so as to be disposed at the part beyond the sinker 3 coincides with the rear end of the opened latch *a* and prevents the loop b₂ caught on the latch from slipping off onto the stem.

The other needle N₁ which was not selected (or not previously advanced as in the case of the needle N₂)

advances to the position of FIG. 6(II) in accordance with the needle path *x*, where the forward end of its hook projects very slightly beyond the sinker 3.

From the position of FIG. 6(II), the needle N₂ advances sideways in accordance with the needle path *y*. At this time, the forward end of the needle N₂ is progressively raised by a cam 7 provided on an overhanging arm 6 fixed to the forward part of the carriage 4 to confront the sinker 3, whereby the needle N₂ becomes inclined as shown in the position of FIG. 6(III), being raised slightly higher than the upper end of the sinker 3 in preparation for passing over the sinker. The latch engagement member 5, in coincidence with the inclination of the cam 7, permits the needle N₂ to be thus raised. Furthermore, at the position of FIG. 6(III), a holding leaf spring 8 for pressing the needle N₂ downwardly contacts this needle.

The carriage 4 is provided with a rotating shaft 9 which is installed in approximate alignment with the line of the carriage 4 as shown in FIG. 6(III). A gear 10 fixed to one end of said shaft 9 is caused, as the carriage 4 travels, to mesh with the needle slot of the needle bed 1 and forcibly rotate the shaft 9 in one direction. On the other end of the shaft 9, there is fixed a rotating member 11 from which pressing pins 12 for forcibly pressing only the raised needles N₂ in the rotational direction thereof protrude outwardly. The pin 12 presses the needle N₂ which has arrived at the position of FIG. 6(III) in the direction opposite to the direction of advance of the carriage 4. Consequently, as shown in FIG. 4, the forward part of this needle passes over the sinker 3 and, moreover, as indicated on line IV in FIG. 1, quickly drops into the stepped low part 7a of the sum 7, being assisted by the downward force of the pressing leaf spring 8, whereby the needle N₂ is superposed in a crossed state over the adjacent needle N₁ and cannot return to its original position between the adjacent sinkers 3. As a result, the loop b₂ caught in the latch *a* of the needle N₂ confronts the extreme end of the hook of the needle N₁ and opens its eye.

The needle N₁ which is caused by the advance cam to advance from the vicinity of the position of FIG. 1(III) along the inclined forward advance part of the needle path *x* advances to approximately the tuck position in the vicinity of the position of FIG. 6(V) and is inserted through the eye of the loop b₂ caught on the needle N₂.

The latch engagement member 5 which has been supporting the passing of the loop b₂ over the latch in the positions of FIGS. 6(II) and 6(III) is not present in the position of FIG. 6(IV) and subsequent positions. Instead, in the positions of FIGS. 6(IV) and 6(V), a brush wheel 13 for holding the knitted fabric contacts the forward part of the loop b₂ so as to cause the loop to retreat. Consequently, the loop b₂ caught on the needle N₂ moves back slightly and is transferred from the latch *a* onto the stem.

Between the position of (V) and (VI) of FIG. 1, an upward projection 7b of the cam 7 is provided following the low part 7a, and, moreover, the loop transfer needle path *y* is in the retracted position because of the guiding effect of a centre cam. Consequently, the needle N₂ is caused by the upward projection 7b to be raised again to a level higher than that of the sinker 3 and, as it is so supported, retracts in accordance with the needle path *y* to the position of the FIG. 6(VI). The other needle N₁ is caused by the needle path *x* traversing directly across the lower surface cut-out of the centre cam and by a cut-out 7c formed in the lower surface of the upward projection 7b of the cam 7 to pass to the vicinity of the position of FIG. 6(VII), to be described hereinafter, without changing the advance position at approximately the tuck position. That is, the needle N₁, with the loop maintained in the positional state on the tip of the latch of the open hook, travels through the needle bed up to a point near the position of FIG. 6(VII).

Since the needle path *y* is caused to retreat by a retreat

cam at a point after the position of the FIG. 6(VI), needle N_2 guided by this needle path retracts from the needle bed forward edge 2 and completely casts off the loop b_2 from the back of the latch a . Simultaneously, the needle N_2 disengages from the upward projection 7b of the cam 7 and is caused by the elastic energy stored therein when it passed over the sinker 3 to return to its original position between sinkers. Thus, the loop b_2 is transferred completely into the hook of the needle N_1 , whereupon the automatic loop transfer is completed as shown in FIG. 6(VIIa).

There may be some instances wherein the needle N_2 , immediately upon moving onto the upward projection 7b in the vicinity of the position of FIG. 6(VI), is caused by the elastic energy stored therein to return over the previously passed over sinker 3 thereby to return to its original position between its adjacent sinkers. In such a case, however, the loop b_2 is stretched between both needles N_1 and N_2 and is spread, so that complete loop transfer occurs in the vicinity of position of FIG. 6(VII).

Since the needle paths x and y become confluent at a point after the position of FIG. 6(VII), the needle N_1 , still holding the loops b_1 and b_2 in its hook, retreats to a position near the needle bed forward edge 2, while the needle N_2 which has cast off the loop b_2 moves slightly forward and assumes approximately the same position of alignment.

Referring to FIGS. 7 through 11, inclusive, showing the second embodiment of the invention, the arrangement of the latch needles N_1 and N_2 in the needle bed 1 is the same as that in the example illustrated in FIGS. 1-6, and the essential features thereof are shown in FIGS. 7 and 11(Ia). The needle N_1 passes along a needle path x of a carriage 24, and the needle N_2 is caused to pass along a loop transfer needle path y .

As shown in FIG. 11(I), the needles N_1 and N_2 which have entered the needle paths x and y advance and assume their respective positions shown in FIG. 11(II), the needle N_2 being so positioned that the rear end of its open latch a is approximately at the same position as the sinker 3 thereby to hold the loop b_2 and prevent it from slipping onto the stem.

During the advance from the position of FIG. 11(II) to the position of FIG. 11(III), the forward end of the needle N_2 is progressively raised by a cam 27 provided on an overhanging arm 26 fixed to the carriage 24, being inclined at its forward part as shown so that it is slightly higher than the upper end of the sinker 3, and thereby being readied for passing over the sinker.

Needle guide slots 25, 25 formed in the needle bed 1 for passing each pair of adjacent needles N_1 and N_2 are connected by an intercommunicating slot 25a as shown in FIG. 10. When, at the position of FIG. 11(III), the needle N_2 is in the raised position as described above, it is in a state wherein it is capable of entering the intercommunicating slot 25a.

Past the position of FIG. 11(III), since a brush 28 makes contact and becomes a resistance member, the needle N_2 is pushed in the direction of travel of the carriage 24 and, passing over the sinker 3, is superposed diagonally above the adjacent needle N_1 as shown in FIG. 11(IIIa). Successively thereafter, the descending inclination 27a of the cam 27 in the interval from the position of FIG. 11(III) to the position of FIG. 11(IV) causes the needle N_2 to descend as indicated in FIG. 11(IV), the needle N_2 thereby being so positioned that the loop b_2 caught on its latch a is in a position confronting the tip of the hook of the needle N_1 similarly as in the case of the aforescribed embodiment of the invention.

The advance of the needle path y in the interval between the positions of FIGS. 11(IV) and 11(V) causes the needle N_2 to advance slightly. At the same time, a brush wheel 33 contacts the knitted fabric and pushes the loop b_2 back toward the needle bed forward edge 2.

Consequently, the loop b_2 is cast off positively from the latch a and is transferred onto the stem.

Since, in the interval from the position of FIG. 11(V) to the position of FIG. 11(VI), the needle path x is caused by an advance cam to advance, the needle N_1 advances as the loop b_2 is held by the brush wheel 33, and the forward end of its hook passes through the eye of the loop b_2 caught on the needle N_2 .

Throughout the interval from the position of the FIG. 11(III) through the position of FIG. 11(VI), the brush 28 continuously exerts a sideward force on the needle N_2 .

In the interval from the position of FIG. 11(VI) through the position of FIG. 11(VII), the upward projection 27b causes the needle N_2 to rise to a position slightly higher than the sinker 3 similarly to the position of FIG. 11(III). In the interval from the position of FIG. 11(VII) through the position of FIG. 11(VIII), the needle N_2 is lowered by a triangular cam 27c provided on the upward projection of 27b of the cam 27, and, at the same time, the resistance of the triangular cam 27c causes the forward part of the needle N_2 to return over the previously passed over sinker 3 in the direction opposite to that of the travel of the carriage 24, thereby returning to its original position between its adjacent sinkers 3. The other needle N_1 is again guided in advancing movement by the needle path x and thereby caused to advance toward a cut-out part 27d provided on the lower surface of the upward projection 27b of the cam 27.

Then, as described hereinabove, the retraction of the needle N_2 and the advance of the needle N_1 cause the hook of the needle N_1 to pass through the eye of the loop b_2 caught on the needle N_2 , and, at the same time, the latch a of the needle N_2 is closed by the loop b_2 , whereby the needle N_2 is readied for casting off the loop b_2 . The triangular cam 27c, in actual effect, imparts a guiding action as indicated by chain line in FIG. 7 with respect to the needle path y .

In the interval between the position of FIG. 11(VIII) and the position of FIG. 11(IX), the needle path y is caused to retreat by the guiding effect of a retreat cam, and the needle N_2 is retracted rearwardly from the sinker 3, whereby the loop b_2 is cast off forwardly from the back of the latch a of the needle N_2 . At substantially the same time, the needle N_2 disengages from the upward projection 27b of the cam 27, and the forward part thereof is returned to the normal state from the raised state of the position of FIG. 11(VI) and thereafter. Consequently, the loop b_2 , together with the loop b_1 , is caught within the hook of the needle N_1 , whereupon a full loop transfer is completed as indicated in FIG. 11(IXa). Thereafter, the confluence of the needle paths x and y cause both needles N_1 and N_2 to be aligned in substantially the same positions.

Referring to FIGS. 12, 13, and 14 showing the essential construction and arrangement of the third embodiment of the invention, each of the latch needles N is provided with an engagement part Na formed on its stem slightly to the rear of the tip of the opened latch a as shown. The selection of certain needles from among the needles N to produce the arrangement of N_1 and N_2 is the same as that in the aforescribed first embodiment of the invention.

The needles N_1 and N_2 which have entered the needle paths x and y from the position shown in FIG. 14(I) respectively advance to their positions shown in FIG. 14(II). The advance of the needle N_2 causes its loop b_2 to be shifted from its latch a onto its stem and be caught by the engagement part Na , whereby the loop b_2 is drawn forwardly. At the same time, the forward part of the needle N_2 is raised slightly above the sinker 3, similarly to the first embodiment of the invention, by a cam 47 on an overhanging arm 46 of the carriage 44.

As the needles advance from the position of FIG. 14(II) to the position of FIG. 14(III), the combination of a rotating shaft 49, a gear 50, a rotating member 51, a pressing pin 52 on the rotating member 51, and a pressing wire

spring 48 having the same function as equivalent parts in the first embodiment of the invention operate to push the needle N₂ in the direction opposite to that of the travel of the carriage 44, whereby the needle N₂ passes over the sinker 3 and is superposed over the adjacent needle N₁. Since the end of the cam 47 is simultaneously reached, the needle N₂ descends as shown in FIG. 14(IV), being assisted by the pressing wire spring 48, and crosses over the needle N₁, thereby positioning the eye of the loop b₂ immediately in front of the forward end of the hook of the needle N₁ in preparation for loop transfer.

In the interval from position of FIG. 14(IV) to position of FIG. 14(V), the needle N₁ is guided by the needle path x and passes its hook end through the eye of the loop b₂ and, simultaneously, assumes an advanced position which is slightly rearward of that of the needle N₂, thereby shifting the loop b₁ which it held previously from the latch a onto the stem. The other needle N₂ moves onto a cam 54 provided on an overhanging arm 46 in correspondence with the forward part of the advanced end of the needle N₁ and is thus prepared for being again raised. The action of the brush wheel 53 (FIG. 12) is the same as the brush wheel 13 in the case of the first embodiment of the invention.

In the interval from position of FIG. 14(V) through position of FIG. 14(VI), only the needle N₁ is caused by the needle path x to retract slightly and causes the loop b₁ to be inapproximate engagement with the rear end of the opened latch a in preparation for the closing movement thereof. The other needle N₂ is raised by the inclination of a cam 54 to a position slightly higher than the sinker 3 similarly to the position of the FIG. 14(II). Then, at the same time that it is thus raised, the needle N₂ is caused by the elastic energy stored therewithin to return over the previously passed over sinker 3 and thereby to return to its original position between its adjacent sinkers.

Then, when the end of the cam 54 is reached in the position of the FIG. 14(VII), the needle N₂ has descended to the same height as the needle N₁, and the loop b₂ is disposed across the stem to the rear of the latch a of the needle N₂ and the interior of the hook of the needle N₁ as indicated in FIG. 14(VIIIa).

In the interval from position of FIG. 14(VII) through position of FIG. 14(VIII), since the needle paths x and y become confluent, the needles N₂ and N₁ retract simultaneously to the rear part of the sinker 3. The needle N₂ casts off the loop b₂ from the back of the latch a, and, at the same time, the needle N₁ casts off the loop b₁ from the back of the latch a as the hook of the needle N₁ holds the loop b₂. As a result, the loop b₂ is passed under and through the loop b₁ thereby to form a new knitting loop c.

Referring to FIGS. 15 through 20, inclusive, the example of the knitting machine according to the invention shown therein is provided with a needle bed 1, along whose forward edge there are parallelly aligned a row of a large number of sinkers 3, between which there are alternately aligned latch needles N capable of sliding in their forward and rearward directions. Each of the needles N is so guided by a needle guide slot 62 provided at the forward part of the needle bed 1 and has a shape which is sufficiently great in the vertical direction that the forward part of said needle can move upwardly to a height higher than the upper ends of the above mentioned sinkers 3. Furthermore, the forward part of each needle N can be shifted over an adjacent sinker 3, against the elastic force of the needle itself, to be inserted into a position between the neighbouring sinkers needles on one side thereof.

The needle bed 1 is further provided at its forward part with a needle holder 63 made of an elastic material such as sponge rubber which engages from above the stems of all needles N and constantly presses downwardly on all needles N so as to hold them in their downward positions. Across the upper surface of the needle bed 1, a latch-needle actuating carriage 64 is so mounted as to be slideable in the longitudinal direction of the needle bed.

The carriage 64 has on its reverse side a rear partition wall 65, which extends along the length of the carriage 64 forward of a rear non-knitting passage which permits the passage of the batts of non-knitting needles at the most rearward position of the needle bed. A front partition wall 66 is disposed forward of the rear partition wall 65 and extends along the length of the carriage 64 forward of the position to which the batts B of the needles N of a needle selection position F are guided and introduced, the position F being advanced up to a position immediately forward of that for latch extraction from the knitting preparation position E advanced forward of the most rearward position of the needle bed. A triangular cam 67 projecting rearwardly is provided at approximately the centre part 15 of the wall 66.

In symmetrical arrangement on the left and right sides of the triangular cam 67 and between the rear partition wall 65 and front partition wall 66, there are provided retraction cam members 68, 68 for producing retreating motion. At the outermost parts at the left and right ends of the carriage 64, there are provided needle dividing cams 69, 69 for dividing the needles N at the knitting preparation position E and the needle selection position F. At 20 three places on each side, namely, outer parts near the needle dividing cams 69, 69, intermediate parts inside thereof, and innermost parts, there are formed, respectively, outer retraction cams 70, 70, intermediate retraction cams 71, 71, and inner retraction cams 72, 72.

Advancing cams 73, 73, are provided between the retraction cams 68, 68 and the rear partition wall 65. On the outer sides of the advancing cams 73, 73, there are formed outer advancing cams 74, 74 for engaging with the batts B of the needles N at the knitting preparation position E and causing the needles N to advance to the position immediately forward of that for latch disengagement thereby to guide and introduce the needles to the outer retraction cams 70, 70. On the inner sides of the outer advancing cams 74, 74, there are formed inner advancing cams 75, 75 for causing the needles N which have been caused to retract by the outer retraction cams 70, 70 to advance slightly again and guiding and introducing the needles N to the intermediate retraction cams 71, 71.

By the above described cam arrangement, the batts B of the knitting needles N at the knitting preparation position E are guided on the path designated by line G—G as shown in FIG. 15, while the batts B of the needles N at the needle selection position F are guided on the path designated by line J—J. In the path G—G, there are provided needle pressing cams 76, 76 which project downwardly and function to engage with the upper part of the batts B of the needles N and press and hold the needles N in a low position.

Along the forward part of the carriage 64, there is formed a channel part 77 which has an open side facing rearwardly. On the left-hand and right-sides on the upper surface of the lower flange part 77a of this channel part 77, there are provided needle lifting cams 78, 78 of approximately S shape, and inclined parts 78a, 78a sloping downwardly are formed on the outer sides of the cams 78, 78. Furthermore, on the inner sides of the cams 78, 78, there are formed cut-out parts 78b, 78b which are substantially perpendicular to the upper surface of the lower flange part 77a, and which, engaging with the forward parts of the needles N guided and introduced into the path J—J, lift the forward parts of the needles to a position slightly above the upper ends of the aforementioned sinkers 3.

Auxiliary needle lifting cams 79, 79 are provided at positions rearward of and slightly inside of the needle lifting cams 78, 78. Downwardly sloping inclined parts 79a, 79a and 79b, 79b are formed outside and inside of the cams 79, 79 and, engaging with the forward parts of the needles 70 guided and introduced into the path G—G, lift said forward

ward parts slightly, whereby the difference in height of the forward parts of the latch needles lifted by the auxiliary needle lifting cams 79, 79 and those of the latch needles lifted by the needle lifting cams 78, 78 is made small thereby to prevent slack in the loops on latch needles lifted by the needle lifting cam 78, 78.

Needle raising cams 80, 80 are provided inside of the auxiliary needle lifting cams 79, 79 and function to raise again the knitting needles N which, having disengaged from the needle lifting cams 78, 78, are positioned on the auxiliary needle lifting cams 79, 79 and have been guided and introduced into the path J—J to a position above the upper ends of the sinkers 3.

The above described needle lifting cams 78, 78, the auxiliary needle lifting cams 79, 79, and needle raising cams 80, 80 are fabricated integrally from a single sheet of steel.

Needle actuating cams 81, 81 are fixed on the left and right sides on the rear surface of the web part 77b of the channel part 77 and, engaging with the forward parts of the needles N which have been lifted by the needle lifting cams 78, 78 and are in the path J—J, function to shift said forward parts, as the carriage base plate 64 is shifted, forcibly in the same direction.

When the forward parts of the needles N shifted by the needle actuating cams 81, 81 pass over the tips of the adjacent needles N in the path G—G on the side in the direction of travel of the carriage as indicated in FIG. 20, the shifted needles N are caused by the cut-out parts 78b, 78b of the needle lifting cams 78, 78 to disengage from the needle lifting cams 78, 78 and move downwardly, thereby disengaging from the needle actuating cams 81, 81 and stopping in the disengaged position. That is, there is constituted a disengaging mechanism which, through the action of the cut-out parts 78b, 78b of the needle lifting cams 78, 78, causes the needles N to disengage from the needle actuating cams 81, 81. The needles N which have been disengaged by this disengaging mechanism from the needle actuating cams 81, 81 engage at their forward parts with the hooks of respectively adjacent needles N in the path G—G and assume the coupled position as indicated in FIG. 19(d).

An elastic plate 82 is fixed to the lower surface of the upper horizontal part of the carriage 64 at its forward part. Until the needles which have been guided in the path J—J disengage from the needle lifting cams 78, 78, the elastic plate 82 is engaged with the lower part of the opened latches of these needles N and lifts said latches slightly, thereby holding the needle loops K suspended from the upper parts of the opened latches of the needles N and preventing said loops from being pushed behind the latch. Furthermore, while the elastic plate 82 is preventing the loops from being pushed behind the latch as stated above, it is constantly pressing the said needles N downwardly and, in cooperation with the aforementioned needle holder 63, compels these needles to descend when they disengage from the needle lifting cams 78, 78.

The needle loop transfer mechanism of the above described arrangement and construction according to FIGS. 15 to 20 operates in the following manner.

First, by means of a known needle selection device in general use, a large number of latch needles N are selectively divided into needles N₁ the knitting preparation position E and needles N₂ the needle selection position F in the ratio of, for example, one to one, and needle loops K suspended from the needles N₂ are transferred to the respectively neighbouring needles N₁. That is, in order to transfer a needle loop K toward the right as indicated in FIG. 19, the carriage 64 is moved in sliding motion from left to right toward the selectively separated group of the needles, that is, in the direction of the arrow M shown in FIGS. 15, 19(a), and 20.

The operation of the knitting machine will be further

described hereinafter with particular reference to FIGS. 19(a) through 19(h), inclusive, and FIG. 20. FIGS. 19(a) through 19(h), inclusive, indicate the needle loop transfer operation of the needles as viewed in sections resulting from cutting the carriage 64 along the lines a through h shown in FIGS. 15 and 18. FIG. 19(a) shows the disposition of latch needles at the time when latch needles are selectively separated.

As the carriage 64 is moved from position a and reaches position b, the knitting needle N₁ is caused by the outer advancing cam 74 to advance to a position slightly to the rear of the position immediately before the loops are pushed behind the latch. At the same time, the outer inclined part 79a of the auxiliary needle lifting cam 79 causes the forward part of the needle N₁ to begin to lift slightly against the elastic force of the needle holder 63. Similarly, the needle N₂ is caused by the needle lifting cam 78 to be lifted against the elastic force of the needle holder 63 to a position above the upper end of the sinkers 3.

Then, as the carriage 64 is moved from position b to position c, the needle N₁ is lifted by the auxiliary needle lifting cam 79, and, at the same time, the tip of the needle N₁ is caused by the outer retracting cam 70 to retract until it is positioned in alignment with the line of the sinkers 3. On one hand, the needle N₂, having been lifted by the needle lifting cam 78 and sustained by the action of the elastic plate 82 in the state immediately before the loops are pushed behind the latch, engages with the needle actuating cam 81.

When, by the travel of the carriage 64, the position d is reached from position c, the knitting needle N₁ is maintained in the above described state, but the forward part of the needle N₂ is forcibly caused by the needle actuating cam 81 to shift in the direction of travel of the carriage. The needle N₂ thereupon assumes the position shown in FIG. 20 and, immediately thereafter, is disengaged from the needle lifting cam 78 by the action of the disengaging mechanism, that is, by the cut-out part 78b of the needle lifting cam 78. At the same time, the needle N₂ disengages from the needle actuating cam 81 and is stopped in its shifted position and, moreover, is caused by the effect of the needle holder 63 and the elastic plate 82 to engage with the side of the hook of the needle N₁ on the side of the carriage travel direction and be superposed above the needle N₁ as shown. At this time, the needle N₁ is elastically pressed in contact with the sinker 3 by the elastic force of the needle N₂ urging it to return to its original position between adjacent sinkers 3. Furthermore, the forward end of the knitting needle N₁ is positioned to the rear of the needle loop K suspended from the needle N₂.

As the carriage 64 continues to move and the position changes from d to e, the needle N₁ is caused by the inner advancing cam 75 to advance, whereupon its forward end passes through the needle loop suspended from the needle N₂ and advances. At the same time, the needle N₁ disengages from the auxiliary needle lifting cam 79 and descends to a lower position, while the needle N₂, still engaged with the needle N₁, is maintained in a state of immobility in the forward-rearward direction.

As the travel of the carriage 64 is further continued from position e to position f, the needle N₁, at its advanced position due to the inner advancing cam 75, is forcibly pressed by the action of the needle pressing cam 76 which engages with the batt of the needle N₁ to the lower part of the needle bed. During this operation, the needle N₂ is caused by the needle raising cam 80 to rise to a position higher than the upper ends of the sinkers 3. At this time, the needle N₂ is forcibly disengaged from the needle N₁ which has been forcibly pressed downwardly. At the same time the rising movement of the needle N₂ is transmitted through the needle loop K to the needle N₁, which is thereby urged to rise together with the needle N₂ but is prevented from thus rising by the needle pressing

cam 76. The needle N_2 which has been raised by the needle raising cam 80 is automatically returned by the force due to the elastic energy stored therein to its original position between adjacent sinkers, the needle loop K still being suspended from the needle N_2 as it is maintained in the position immediately before being pushed behind the latch.

Then, as the carriage 64 travels further and the position changes from f to g , the needle N_1 is caused by the intermediate retracting cam 71 to retract its tip to a position rearward of the sinker 3, that is, to approximately the knitting preparation position E. At the same time, the needle loop K is caught on the hook of the needle N_1 . During this operation since the needle N_2 is placed in an immobile state, and only the needle N_1 retracts, the needle loop K is stretched, whereby the needle loop K is pushed behind the latch from the knitting needle N_2 and is shifted onto the needle stem.

With further travel of the carriage 64 to change the position from g to h , the needle N_1 is maintained in the above described state, while the needle N_2 is caused by the triangular cam 67 and the inner retracting cam 72 of the other retraction cam 68 to retract to the knitting preparation position E in a manner similar to that of the needle N_1 . At this time, the needle loop K is removed from the needle N_2 and is transferred to the needle N_1 .

By successively carrying out transfers of the needle loops in the above described manner, and then carrying out knitting by means of a carriage of a known type for ordinary knitting, it is possible to produce knitted fabrics with openings, that is, lace knitted fabrics.

Conversely, when it is desired to transfer the needle loop K in the left direction, opposite to that described above, a large number of latch needles N are selectively separated as described hereinbefore, and then the carriage 64 is moved from right to left, that is, in the direction opposite to that of the arrow M shown in FIGS. 15, 19(a), and 20, whereby the same operation and result as described above can be obtained.

As a further embodiment of the invention, it is possible to obtain the shifting and approaching action of a pair of mutually adjacent latch needles also by the use of a latch needle actuating carriage such as that illustrated as one example in FIGS. 15 through 20, inclusive, in the manner indicated in FIG. 21. More specifically, of two mutually adjacent latch needles N_1 and N_2 of a pair to be caused to undergo mutual movement, the needle N_2 to be shifted, at least at its hook end part, is first raised from the position shown in FIG. 21(a) to that of FIG. 2(b), and then the needle N_2 is passed through the position shown in FIG. 21(c) and transferred to the position of FIG. 21(d). Thereafter, the needle is returned through the positions of FIG. 21(e), (f), and (g), thereby causing it to retreat to assume the position shown in FIG. 21(h).

When the shifting, approaching, and relative movements of the pair of mutually adjacent latch needles are being carried out to form an opening in the knitted fabric, the needle loop K suspended from one latch needle which has been shifted is positioned to confront forward end of the other adjacent needle. Accordingly, this adjacent needle is in a state wherein it can positively pass through said needle loop, whereby the needle loop transfer operation can be accomplished in a very accurate manner.

In the above described case, by arranging and constructing the mechanism for operating the latch needle actuating carriage so that only when the latch needle carrying the needle loop positions its loop to confront the tip part of the adjacent needle and, after insertion of this adjacent needle in the loop, returns to its original position between sinker elements while still holding the loop, the relative movement in the sliding direction of this needle and loop is produced, the durability of the needle bed and the mechanism for producing the above described sliding movement is substantially increased, and, moreover, the carriage can be caused to slide smoothly.

Furthermore, in some cases when the needle N_2 is to

be shifted to the position shown in FIG. 21(d), difficulty is encountered in bringing the loop K suspended therefrom to a position accurately confronting the mutually adjacent needle N_1 . This difficulty can be simply and effectively overcome by providing in the needle actuating carriage a needle raising cam for raising at least the forward hook part of the non-shifting needle N_1 . For this needle raising cam, members 78 and 79 in the example illustrated in FIGS. 15 through 20, inclusive, can be utilized.

As disclosed above with respect to embodiments, the present invention provides a knitting machine of latch needle type arranged and constructed to accomplish an operation comprising: moving at least the forward part of one of two adjacent latch needles from its normal advance-retreat path; moving said forward part to a position between the sinker elements above the other latch needle by passing it over a sinker element thereby to cause the two needles to be superposed at least at the forward parts of said needles; at the same time, causing a loop suspended from said one needle to confront the front part of the front end of the hook of said other needle; causing the two needles to undergo forward and rearward movements to transfer the loop suspended on said one needle to said other needle; simultaneously extracting said one needle from its loop, thus completing loop transfer in a completely automatic manner and further causing said one needle to return to its original position between adjacent sinkers.

The above described series of operational steps of the two latch needles can be accomplished merely by selecting one of the latch needles by means of a needle selecting means as described with respect to the embodiments of the invention. Therefore, the present invention provides a knitting machine wherein loop transfer between adjacent needles to form an opening in the knitted fabric is facilitated and made accurate, and whereby knitting such as lace knitting and knitting of lace patterns is greatly facilitated.

It should be understood, of course, that the foregoing disclosure relates to only preferred embodiments of the invention and that it is intended to cover all changes and modifications of the examples of the invention herein chosen for the purposes of the disclosure, which do not constitute departures from the spirit and scope of the invention as set forth in the appended claims.

What I claim is:

1. A knitting machine comprising in combination: a needle bed; a plurality of sinker elements aligned in a row and at equal intervals across the forward edge of the needle bed in the longitudinal direction thereof; a plurality of latch needles aligned in a row in said needle bed and positioned alternately between the sinker elements and slideable forwardly and rearwardly in a direction perpendicular to the longitudinal direction of said needle bed; a knitting carriage having a cam mechanism thereon engaging said latch needles for accomplishing a knitting operation movable reciprocably along the needle bed in the longitudinal direction thereof to actuate the latch needles in succession; a latch needle actuating carriage mounted on said needle bed and slideable thereon in the longitudinal direction thereof; a further cam mechanism attached to said needle actuating carriage engaging the latch needles for causing predetermined latch needles spaced at intervals of at least one needle from among said latch needles to move relative to the remaining latch needles so that at least at their forward end parts approach adjacent latch needles; means on said latch needle actuating carriage for shifting at least the forward end part of each of the predetermined latch needles laterally relative to an ad-

13 jacent latch needle to a position between the respective sinker elements where said adjacent latch needle is positioned, said further cam means causing the two latch needles thus positioned between the same sinker elements to undergo relative motion in their sliding direction for causing one of said two latch needles to be inserted through a needle loop suspended from the other of said latch needles, and causing the needle which has been carrying said loop to be withdrawn therefrom, thereby transferring the loop to the other needle.

2. A knitting machine according to claim 1, in which said means on the latch needle actuating carriage is a still further cam means which has a configuration for shifting one of each pair of mutually adjacent needles sidewise, at least at its forward end part, to approach the other needle.

3. A knitting machine according to claim 1, in which said means on the latch needle actuating carriage has a configuration to enable the latch needle which has been shifted to return to its original position between sinker elements.

4. A knitting machine according to claim 1, in which said further cam mechanism has a shape for causing a predetermined latch needle to project beyond the forward edge of the row of sinker elements, and said means engaging the forward end part of said projecting latch needle, thereby causing said needle to shift in the longitudinal direction of the needle bed and to approach to the adjacent latch needle.

5. A knitting machine according to claim 1, in which each of the latch needles is elastically supported in the needle bed to be elastically flexible at least in the longitudinal direction of the needle bed and elastically restorable to its original state.

6. A knitting machine according to claim 1, in which said means on the latch needle actuating carriage has a shape for causing at least the forward hook part of the one latch needle to be shifted to pass by the other needle and shift to a position above and contiguous thereto, causing the loop of the formed needle to be positioned at the forward end of the latter needle, and thereafter when relative movement is imparted to both needles carrying out transfer of said loop from one needle to the other needle.

7. In a knitting machine having a single flat needle bed, and a plurality of sinker elements aligned in a row at constant intervals across the forward edge of the needle bed in the longitudinal direction thereof, the combination of a plurality of latch needles aligned between the sinker elements in the needle bed and slidable forwardly and rearwardly perpendicularly to the longitudinal direction of the needle bed, at least the forward end portion of each of said latch needles being laterally shiftable beyond the centerline of a sinker element adjacent to said each latch needle, means for relatively forwardly moving each of a plurality of latch needles selectively spaced at intervals of at least one needle, means for laterally shifting at least the forward end portions of said forwardly moved needles to cause the forward end portions of the latch needles to approach adjacent needles and means for relatively actuating each pair of said two needles in the forward or rearward direction for transferring a loop suspended on one needle of said two needles to the other needle.

8. In a knitting machine having a single flat needle bed, and a plurality of sinker elements aligned in a row at constant intervals across the forward edge of the needle bed in the longitudinal direction thereof, the combination of a plurality of latch needles aligned between the sinker elements in the needle bed and slidable forwardly and rearwardly perpendicularly to the longitudinal direction of the needle bed, at least the forward end portion of each of said latch needles being laterally shiftable beyond the centerline of a sinker element adjacent to said each latch needle, means for relatively forwardly moving each

5 of a plurality of latch needles selectively spaced at intervals of at least one needle, means for laterally shifting at least the forward end portions of said forwardly moved needles to cause the forward end portions of the latch needles to approach adjacent needles and means for relatively actuating each pair of said two needles in the forward or rearward direction for inserting the forward end portion of one needle of said two needles into a loop suspended on the other needle and to withdraw the last-mentioned needle from said loop, thereby to transfer the loop onto one needle from the other needle.

10 9. In a knitting machine having a single flat needle bed, and a plurality of sinker elements aligned in a row at constant intervals across the forward edge of the needle bed in the longitudinal direction thereof, the combination of a plurality of latch needles aligned between the sinker elements in the needle bed and slidable forwardly and rearwardly perpendicularly to the longitudinal direction of the needle bed, at least the forward end portion of each of said latch needles being laterally shiftable beyond the centerline of a sinker element adjacent to said each latch needle, means for relatively forwardly moving each of a plurality of latch needles selectively spaced at intervals of at least one needle, a latch needle actuating carriage 15 slidably mounted on said needle bed for sliding in the longitudinal direction thereof, said latch needle actuating carriage having means thereon for laterally shifting at least the forward end portion of each of said forwardly moved needles to cause the forward end portion of the latch needle to approach a needle adjacent to said forwarded needle, and means for relatively actuating said two needles in the forward or rearward direction for transferring a loop suspended on one needle of said two needles to the other needle.

20 10. In a knitting machine having a single flat needle bed, and a plurality of sinker elements aligned in a row at constant intervals across the forward edge of the needle bed in the longitudinal direction thereof, the combination of a plurality of latch needles aligned between the sinker elements in the needle bed and slidable forwardly and rearwardly perpendicularly to the longitudinal direction of the needle bed, at least the forward end portion of each of said latch needles being laterally shiftable beyond the centerline of a sinker element adjacent to said each latch needle, means for relatively forwardly moving each 25 of a plurality of latch needles selectively spaced at intervals of at least one needle, a latch needle actuating carriage slidably mounted on said needle bed for sliding in the longitudinal direction thereof, said latch needle actuating carriage having means thereon for laterally shifting at least the forward end portion of each of said forwardly moved needles to cause the forward end portion of the latch needle to approach a needle adjacent to said forwarded needle, and means for relatively actuating said two needles in the forward or rearward direction for transferring a loop suspended on one needle of said two needles to the other needle.

30 11. In a knitting machine having a single flat needle bed, and a plurality of sinker elements aligned in a row at constant intervals across the forward edge of the needle bed in the longitudinal direction thereof, the combination of a plurality of latch needles aligned between the sinker elements in the needle bed and slidable forwardly and rearwardly perpendicularly to the longitudinal direction of the needle bed, at least the forward end portion of each of said latch needles being laterally shiftable beyond the centerline of a sinker element adjacent to said each latch needle, means for relatively forwardly moving each 35 of a plurality of latch needles selectively spaced at intervals of at least one needle, a latch needle actuating carriage having means thereon for advancing each selected needle together with a loop suspended on said needle to advance said loop to a point ahead of the forward edge of said sinker elements, whereby said loops can be shifted at the forward edge of the row of said sinker elements in the longitudinal direction of the needle bed, means for laterally shifting at least the forward end portion of each of said forwardly moved needles to cause the forward end portion of the latch needle to approach a needle adjacent to said forwarded needle, and means for relatively actuating said two needles in the forward or rearward direction for transferring a loop suspended on one needle of said two needles to the other needle.

40 12. In a knitting machine having a single flat needle bed, and a plurality of sinker elements aligned in a row at constant intervals across the forward edge of the needle bed in the longitudinal direction thereof, the combination of a plurality of latch needles aligned between the sinker elements in the needle bed and slidable forwardly and rearwardly perpendicularly to the longitudinal direction of the needle bed, at least the forward end portion of each of said latch needles being laterally shiftable beyond the centerline of a sinker element adjacent to said each latch needle, means for relatively forwardly moving each 45 of a plurality of latch needles selectively spaced at intervals of at least one needle, a latch needle actuating carriage slidably mounted on said needle bed for sliding in the longitudinal direction thereof, said latch needle actuating carriage having means thereon for advancing each selected needle together with a loop suspended on said needle to advance said loop to a point ahead of the forward edge of said sinker elements, whereby said loops can be shifted at the forward edge of the row of said sinker elements in the longitudinal direction of the needle bed, means for laterally shifting at least the forward end portion of each of said forwardly moved needles to cause the forward end portion of the latch needle to approach a needle adjacent to said forwarded needle, and means for relatively actuating said two needles in the forward or rearward direction for transferring a loop suspended on one needle of said two needles to the other needle.

50 13. In a knitting machine having a single flat needle bed, and a plurality of sinker elements aligned in a row at constant intervals across the forward edge of the needle bed in the longitudinal direction thereof, the combination of a plurality of latch needles aligned between the sinker elements in the needle bed and slidable forwardly and rearwardly perpendicularly to the longitudinal direction of the needle bed, at least the forward end portion of each of said latch needles being laterally shiftable beyond the centerline of a sinker element adjacent to said each latch needle, means for relatively forwardly moving each 55 of a plurality of latch needles selectively spaced at intervals of at least one needle, a latch needle actuating carriage having means thereon for advancing each selected needle together with a loop suspended on said needle to advance said loop to a point ahead of the forward edge of said sinker elements, whereby said loops can be shifted at the forward edge of the row of said sinker elements in the longitudinal direction of the needle bed, means for laterally shifting at least the forward end portion of each of said forwardly moved needles to cause the forward end portion of the latch needle to approach a needle adjacent to said forwarded needle, and means for relatively actuating said two needles in the forward or rearward direction for transferring a loop suspended on one needle of said two needles to the other needle.

60 14. In a knitting machine having a single flat needle bed, and a plurality of sinker elements aligned in a row at constant intervals across the forward edge of the needle bed in the longitudinal direction thereof, the combination of a plurality of latch needles aligned between the sinker elements in the needle bed and slidable forwardly and rearwardly perpendicularly to the longitudinal direction of the needle bed, at least the forward end portion of each of said latch needles being laterally shiftable beyond the centerline of a sinker element adjacent to said each latch needle, means for relatively forwardly moving each 65 of a plurality of latch needles selectively spaced at intervals of at least one needle, a latch needle actuating carriage having means thereon for advancing each selected needle together with a loop suspended on said needle to advance said loop to a point ahead of the forward edge of said sinker elements, whereby said loops can be shifted at the forward edge of the row of said sinker elements in the longitudinal direction of the needle bed, means for laterally shifting at least the forward end portion of each of said forwardly moved needles to cause the forward end portion of the latch needle to approach a needle adjacent to said forwarded needle, and means for relatively actuating said two needles in the forward or rearward direction for transferring a loop suspended on one needle of said two needles to the other needle.

70 15. In a knitting machine having a single flat needle bed, and a plurality of sinker elements aligned in a row at constant intervals across the forward edge of the needle bed in the longitudinal direction thereof, the combination of a plurality of latch needles aligned between the sinker elements in the needle bed and slidable forwardly and rearwardly perpendicularly to the longitudinal direction of the needle bed, at least the forward end portion of each of said latch needles being laterally shiftable beyond the centerline of a sinker element adjacent to said each latch needle, means for relatively forwardly moving each 75 of a plurality of latch needles selectively spaced at intervals of at least one needle, a latch needle actuating carriage

slidably mounted on said needle bed for sliding in the longitudinal direction thereof, said latch needle actuating carriage having means thereon for advancing a loop suspended on said each forwardly moved needle toward a point ahead of the front end of the hook of an adjacent needle and maintaining the loop in said advanced position, means for shifting at least the forward end portion of said advanced loop-carrying needle in the longitudinal direction of the needle bed, means for crossing the forward end portion of said each shifted needle with the other needle adjacent to said shifted needle thereby to cause said loop suspended on said shifted needle to confront the forward end of said unshifted needle, and means for forwardly sliding said unshifted needle thereby to cause said unshifted needle to be inserted into said loop suspended on said shifted needle.

12. A knitting machine comprising a single flat needle bed, a plurality of sinker elements disposed on the forward edge of said needle bed at constant intervals, a plurality of latch needles mounted in said needle bed slidably forwardly and rearwardly between said sinker elements and perpendicularly to the longitudinal direction of said needle bed, each of said latch needles having a hook for suspension of a knitting loop and a latch for opening and closing of said hook in the forward end portion thereof, at least the forward end portion of each of said latch needles being movable up and down and being laterally bendable, means for moving each of a plurality of selected latch needles at spaced intervals forwardly, and actuating means slidably mounted on said needle bed for sliding in the longitudinal direction of said needle bed, said actuating means comprising means for shifting the forward end portions of said selected and forwardly moved needles upwardly, means for laterally bending the forward end portion of each of said upwardly shifted needles over and beyond the sinker element to one side of said needle to cause said needle to approach the adjacent needle at said side thereof, means for downwardly shifting said laterally bent needles to the adjacent needles thereby to cause the forward end portions of said two needles to cross and for holding said bent needles against lateral return motion, means for relatively actuating said crossed needles forwardly or rearwardly to cause the hook of each unbent needle of said crossed two needles to be inserted into a loop suspended on the bent needle and to withdraw said bent needle from said loop, and means for lifting said bent needles upwardly thereby causing them to return to the original positions thereof, whereby a one-way sliding of said actuating means causes the loop to be transferred from one needle to the other, and said knitting machine can thereafter be prepared for ordinary knitting.

13. A knitting machine comprising a single flat needle bed, a plurality of sinker elements disposed on the forward edge of said needle bed at constant intervals, a plurality of latch needles mounted in said needle bed slidably forwardly and rearwardly between said sinker elements and perpendicularly to the longitudinal direction of said needle bed, each of said latch needles having a hook for suspension of a knitting loop and a latch for opening and closing of said hook in the forward end portion of each of said latch needles being movable up and down and being laterally bendable, means for moving each of a plurality of selected latch needles at spaced intervals forwardly, and actuating means slidably mounted on said needle bed for sliding in the longitudinal direction of said needle bed, said actuating means comprising means for shifting the forward end portions of said selected and forwardly moved needles upwardly, means for laterally bending the forward end portion of each of said upwardly shifted needles over and beyond the sinker element to one side of said needle to cause said needle to approach the adjacent needle at said side thereof, means for downwardly shifting said laterally bent needles to the adjacent needles thereby to cause the forward end portions of

said two needles to cross and for holding said bent needles against lateral return motion, means for relatively actuating said crossed needles forwardly or rearwardly to cause the hook of each unbent needle of said crossed two needles to be inserted into a loop suspended on the bent needle, means for lifting said bent needles upwardly thereby causing them to return to the original positions thereof, and means for causing said returned needles to slide to be withdrawn from said loops, whereby a one-way sliding of said actuating means causes each loop to be easily transferred from one needle to the other, and said knitting machine can thereafter be prepared for original knitting.

14. A knitting machine comprising a single flat needle bed, a plurality of sinker elements disposed on the forward edge of said needle bed at constant intervals, a plurality of latch needles mounted in said needle bed slidably forwardly and rearwardly between said sinker elements and perpendicularly to the longitudinal direction of said needle bed, each of said latch needles having a hook for suspension of a knitting loop and a latch for opening and closing of said hook in the forward end portion thereof, at least the forward end portion of each of said latch needles being movable up and down and being laterally bendable, means for moving each of a plurality of selected latch needles at spaced intervals forwardly, and actuating means slidably mounted on said needle bed for sliding in the longitudinal direction of said needle bed, said actuating means comprising means for shifting said selected and forwardly moved needles upwardly together with respective adjacent needles and shifting said selected and forwardly moved needles upwardly higher than said adjacent needles, means for lifting the needle adjacent at one side of said upwardly shifted needles together with the upward shifting of said upwardly shifted needle, means for laterally bending the forward end portion of said selected and forwardly moved needles over and beyond the sinker element on one side of said each needle to cause said portion to approach the adjacent needle on said side, means for shifting said laterally bent needles downwardly while in the bent condition so that the forward end portions of said two needles cross and for maintaining said needles against lateral return motion of said bent needles, means for relatively actuating said crossed needles forwardly or rearwardly to cause the hook of the unbent needle of said crossed needles to be inserted into a loop suspended on the bent needle.

15. In a knitting machine having a single flat needle bed, a plurality of sinker elements aligned in a row at constant intervals along the forward edge of said needle bed, a plurality of latch needles aligned between the sinker elements and each of said needles being slidably forwardly and rearwardly, the improvement comprising means for transferring a loop suspended on each of a plurality of selected needles at intervals of at least one needle to adjacent needles, said transferring means comprising an actuating carriage slidably mounted on said needle bed and slidable in the longitudinal direction thereof, and said actuating carriage further comprising means for laterally shifting the forward end parts of said selected needle across said sinker elements to cause them to approach the adjacent needles, and means for causing said selected needles and their adjacent needles to slide relatively forwardly and rearwardly, whereby a loop on each of said selected needles can be transferred to said adjacent needles.

16. In a knitting machine having a single flat needle bed, a plurality of sinker elements aligned in a row at constant intervals along the forward edge of said needle bed, a plurality of latch needles aligned between the sinker elements and each of said needles being slidably forwardly and rearwardly, the improvement comprising means for transferring a loop suspended on each of a plurality of selected needles at intervals of at least one needle to adjacent needles, said transferring means comprising

an actuating carriage slidably mounted on said needle bed and slidable in the longitudinal direction thereof, and said actuating carriage further comprising means for laterally shifting the forward end parts of said selected needles across the sinker elements to cause them to approach the adjacent needles, and means for causing said selected needles and their adjacent needles to side relatively forwardly and rearwardly in order to insert the forward end portion of said adjacent needles into a loop on said selected needles and thereafter to withdraw said selected needles from said loops.
